UNITED STATES PATENT OFFICE.

LEONARD J. LOHLEIN, OF LUSK, WYOMING.

COMBINED APPLICATOR AND SYRINGE.

SPECIFICATION forming part of Letters Patent No. 702,570, dated June 17, 1902.

Application filed August 1, 1901. Serial No. 70,493. (No model.)

To all whom it may concern:

Be it known that I, LEONARD JOHN LOHLEIN, a citizen of the United States, residing at Lusk, in the county of Converse and State 5 of Wyoming, have invented certain new and useful Improvements in a Combined Applicator and Syringe; and I do declare the following to be a full, clear, and exact description of the invention, such as will enable others 10 skilled in the art to which it appertains to make and use the same, reference being had to the accompanying drawings, and to the letters of reference marked thereon, which form a part of this specification.

15 This invention has relation to improvements in syringes; and it consists in the novel construction, combination, and arrangement of parts of which it is composed, all as will be hereinafter fully explained.

20 The annexed drawing, to which reference is made, fully illustrates my invention, in which the figure represents a vertical sectional view of my device, showing the same adapted for use in special cases.

25 Referring by letter to the accompanying drawing, A designates the cylinder, that is open at the top and bottom, and the upper end thereof is provided with male screw-threads b and a shoulder c, upon which is seated a

30 collar or shield d, that serves as a stop for the cylinder, and above this collar is arranged a flaring tube or hopper f, which is female screw-threaded, as at g, to engage the upper threaded end of the cylinder. Thus by such 35 connection between the hopper and cylinder the collar is held in position. This hopper is also provided with an annular rib or projection h, that strengthens the hopper and also serves as a finger-hold.

40 B designates the plunger-rod, which is provided at its upper end with a ring or handle i and at its lower end with a head j, and the same can be readily used as a syringe as well as an applicator.

45 When it is desired to use the instrument for substituting an article to be used instead of a catamenial sack, the rod is withdrawn from the cylinder and hopper, after which a

sponge is placed within the hopper and the rod again inserted in the hopper above the 50 sponge and the latter forced down the cylinder by pressure upon the rod B until the sponge projects from the lower end of the cylinder about one-eighth of an inch, after which said cylinder is inserted in the vaginal 55 cavity and the operator having placed the forefinger in the ring of the rod forces the rod, which in turn forces the sponge, out of the cylinder and into position, thus closing the cavity, and the cylinder is then withdrawn, 60 leaving the sponge in place, a stop w upon the rod limiting the stroke of the latter in the operation.

It will be observed from the above description that the sponge does not come in contact 65 with the wall of the cavity in inserting the same, but is deposited at the proper place directly from the cylinder, and the device can be used for sanitary purposes as well, and that in case of miscarriage the flow can be in- 70stantly checked by using the device as above described, and instead of a sponge cotton can be used and the mouth of the womb can be closed, and it will be further observed that my device can be readily used as a syringe 75 for sanitary purposes, and it is simple in construction, easily and quickly operated, and at the same time inexpensive to manufacture.

Having thus described my invention, what I claim is—

The combination with the cylinder, provided with the shoulder and threaded upper end, of the hopper having the shouldered and interior threaded lower end; the shield, interposed between the shoulder of the cylinder 85 and the lower end of the hopper; the plunger-rod having the stop w and enlarged female screw-threaded lower end, the whole adapted to operate substantially as described.

In testimony whereof I affix my signature 90 in presence of two witnesses.

LEONARD J. LOHLEIN.
